United States Patent Office.

CHRISTOPHER D. SMITH, OF BRIDGEPORT, CONNECTICUT.

Letters Patent No. 99,362, dated February 1, 1870; antedated January 20, 1870.

IMPROVEMENT IN GAFF-BLOCKS FOR VESSELS.

The Schedule referred to in these Letters Patent and making part of the same.

To all whom it may concern:

Be it known that I, CHRISTOPHER D. SMITH, of the town of Bridgeport, in the county of Fairfield, and State of Connecticut, have invented a new and improved Block to be applied to the end of the gaff, or to the ends of studding-sail booms of a sailing-vessel, for the purpose of preventing the fouling of the sheet attached to the end of the topsail or studding-sails.

The nature of my invention is fully set forth in the accompanying description, reference being had to the accompanying drawings, in which—

Figure 1 represents a longitudinal sectional view of my invention;

Figure 2, a front view; and

Figure 3, a cross-section of fig. 1 at $x-x$.

The same letters refer to the same parts in the several figures.

In the figures shown—

C is the end of wood gaff.

B is the shell of the sheave, having a shank, E, which fits into a ferrule, D, which ferrule is fitted to the end of the gaff, as shown.

Near the end of shank E is a circular groove, F.

A pin, H, is driven through the gaff, so as to enter said groove and prevent the shell of the sheave from falling out, but not to be so snug as to prevent the shell from freely turning in the ferrule.

The sheave A may be either of the common or improved kinds.

The shell and sheave, when in place, can be freely turned on the end of the gaff, so that the sheet passing through the block, can in no event become fouled.

In fig. 4, at I, it will be seen how my improvement is attached to the gaff, and how the sheet is carried through the blocks.

Having thus described my invention,

What I claim therein as new, and desire to secure by Letters Patent, is—

The combination of a block, such as described, with the gaff of a vessel, for the purpose of preventing the fouling of the sheet.

CHRISTOPHER D. SMITH.
